WELL SPUDDER

Erwin A. Campbell, Wexford, Pa., assignor to
 Lee C. Moore Corporation, Pittsburgh, Pa., a
 corporation of Pennsylvania

Application November 21, 1950, Serial No. 196,821

14 Claims. (Cl. 255—11)

1

This invention relates to well spudders. More particularly the invention relates to a hydraulically operated well drilling spudder which is constructed to minimize vibrations in the drilling derrick or mast and to apply the lifting force directly to the drilling tools.

In the usual percussion type drilling rig using a drilling tool, the tool is attached to a cable which runs from a well up to a crown sheave mounted at the top of a derrick and then down to a winding drum on which it is wound and anchored. The winding drum is mounted at the base of the derrick and a drilling machine also mounted at the base of the derrick operates on the section of cable between the crown sheave and the drum. The drilling machine comprises a sheave mounted on a fixed axle to engage the cable and a spudding sheave mounted on a movable axle to engage the cable closely adjacent the fixed sheave. The axle of the movable sheave is usually mounted on an oscillating arm attached to a connecting rod by which it is given a reciprocal motion. The up stroke of the drilling tool is obtained by forcing the movable sheave against the cable to place a link or loop in the cable to draw in the cable from the fixed sheave to the drilling tool and thus lift the cable and drilling tool. The down stroke of the drilling tool occurs when the movable sheave is reciprocated to release the loop to let the cable become straight and allow the drilling tool to fall.

As the drilling machine operates, the cable is subjected alternately to peak loads and loads of low to zero value. In this operation the derrick or mast is subjected to a compressive or downward load which is double the loads applied to the cable because the crown sheave is supporting two lengths of cable and one length always moves in the opposite direction from the other length.

On the down stroke of the drilling tool, the weight of the tool has to raise the length of cable between the winding drum and the crown sheave. This retards the fall of the drilling tool.

The direction of rotation of the crown sheave is reversed twice during each operating cycle. This sheave is usually large in diameter and quite heavy so that its reversal of rotation requires energy from the drilling engine during the up stroke of the tool and the sheave absorbs energy from the tool during the down stroke. This results in decreased useful energy being applied to the drilling tool.

Percussion drilling imparts a peculiar motion

2

to the drilling cable which causes the cable to slip in the groove on the crown sheave when the sheave reverses direction of rotation during the drilling. This slippage results in an injurious wear on both the sheave and the cable. The cable wear is very serious because the cable is an expensive commodity.

The primary object of the present invention is to provide a spudding mechanism for percussion drilling by which the destructive load pulsations on the derrick or mast are reduced and the load and wear on the hoisting mechanism is entirely eliminated.

Another object of the invention is to provide a spudding machine for percussion drilling by which the wear and retarding effect of the crown sheave may be avoided.

A further object of the invention is to provide a hydraulically operated spudding mechanism which may be located at or near the top of a derrick or mast to take the load off the crown sheave and leave the derrick floor free of obstructions.

Still another object of the invention is to provide a hydraulically operated spudding mechanism for percussion drilling which may be located at the top of a derrick and in which the length of the drilling stroke may be widely varied while under the control of an operator on the floor of a derrick.

With these and other objects in view, the invention consists in the spudding mechanism for percussion drilling as hereinafter described, and particularly as defined in the appended claims.

35 The various features of the invention are illustrated in the accompanying drawings in which Fig. 1 is a view in the side elevation, with parts broken away, showing the preferred hoisting machine as applied to a drilling derrick.

40 Fig. 2 is a side elevation of the drilling cable loop-forming and clamping mechanism mounted near the top of a derrick.

45 Fig. 3 is a sectional view of the drilling mechanism shown in Fig. 2 taken on the line III—III of Fig. 2.

Fig. 4 is a plan view of the hydraulic pumps used for supplying pressure fluid for operating the hoisting mechanism.

50 Fig. 5 is a diagrammatic view showing the pumping cylinders and the loop-forming cylinder with the associated piping and valves to illustrate the method of varying the length of the loop-forming stroke, and

Fig. 6 is a side elevation of a modified form

of a drilling cable loop-forming mechanism as applied to a drilling mast.

The present invention is best applied to a drilling derrick in which the cable loop-forming mechanism is mounted at the top of the derrick. Referring to Fig. 1, a drilling cable 10 is taken from the usual bull wheel or other hoisting drum 12 and passes up to a crown sheave 14 mounted on crown blocks 16 resting on the top of the derrick. The cable passes around the sheave 14 and then down through the derrick to a well opening at the bottom of the derrick. The section of the cable passing down from the sheave to the well opening is referred to herein as the drilling section of the cable and this section has the usual stem and drilling bit 18 secured thereto.

The loop-forming cable mechanism is attached to the crown blocks 16 immediately below the crown sheave and is arranged to operate at the upper end of the drilling section of the cable. The loop-forming mechanism consists of a cylinder 20 (see Fig. 2) which is suspended by links 22 and 24 which are pivotally mounted in brackets secured to the bottom of the crown block. A piston 26 (Fig. 5) is mounted within the cylinder 20 and has a stem 28 extending through one end thereof which is bifurcated to receive a sheave 30. The suspension of the cylinder 20 is such that the sheave 28 will normally hang in a position slightly removed from the drilling section of the cable 10. A fixed axis rotatable sheave 32 is mounted in an A-frame 34 which is secured to the crown block 16. The fixed sheave 32 normally loosely engages the cable 10. When the cylinder piston 26 is operated to place a loop in the cable the sheave 30 is moved to the right viewing Figs. 1 and 2, into the dotted line position shown in Fig. 2. At the time that the loop-forming sheave is moved into the dotted line position the cable is gripped between a fixed clamp 36 secured to the bottom of the crown block and a movable clamp 38 which is secured to an arm 40 which is integral with and forms the upper end of the link 24. The link 24 and arm 40 are pivoted on a pin 42 mounted in a bracket 44 secured to the bottom of the crown block 16.

As the piston 26 is moved to force the sheave 30 into loop-forming position, a spring 46 in the cylinder is compressed. The spring 46 acts in conjunction with hydraulic fluid to return the piston 26 back to the front end of the cylinder and leave the sheave 30 in loose engagement with the cable.

To obtain the clamping grip on the cable before the cable loop is formed the first pressure exerted by fluid introduced into the front end of the cylinder acts to move the cylinder bodily to the left, viewing Fig. 2, thus oscillating the arm 40 about the pin 42 and placing the clamping block 38 in clamping position against the cable. This clamping position prevents a further movement of the cylinder to the left and thereafter the sheave 30 moves to the right in forming the cable loop. By this operation the cable is held in fixed position and takes the load impulse, produced by the formation of the cable loop, off of the crown sheave and the section of the cable passing from the crown sheave to the cable drum 12. The full force of the loop-forming operation is imparted to the drilling section of the cable and no energy is used in rotating the crown sheave or moving the section of the cable between the drum and the crown sheave. The clamping mechanism, furthermore, holds the

cable in clamped position until the piston is retracted to release the loop and therefore the crown sheave does not have to absorb the impulse and shock of the drilling stroke.

The loop-forming cylinder is preferably hydraulically operated to give the desired reciprocation of the cylinder piston 26. The hydraulic fluid may be a composition liquid such as oil, alcohols, and glycerine, or a mixture thereof, that is not subject to freezing and which gives a very positive action in the cylinder. The mechanism for producing and delivering fluid pressure to the loop-forming cylinder is illustrated more particularly in Figs. 1, 4 and 5. As shown in Fig. 1, an engine 50, through pulley 52, sprocket 54, chain 56 and sprocket 58, drives a gear 62 which is journaled in a pump frame 64. The gear 62 meshes with a gear 66 mounted on a shaft 66 (Fig. 4) journaled in the pump frame. Crank levers 70 are secured to each end of the shaft 66 and these levers are connected by links 72 to a cross head 74 mounted in guides 76 in one end of the frame 64. A piston rod 78 (Fig. 4) is secured to the cross head 74 and passes through pump cylinders 80 and 82 which are secured in fixed position in the frame 64. Pistons 83 and 84 are mounted on the pump rod 78 within the cylinders 80 and 82 respectively as illustrated in Fig. 5. Accordingly, as the pump rod is reciprocated, the pistons are simultaneously reciprocated in each of the cylinders 80 and 82.

In Fig. 1 is illustrated the piping connections between the pumps 80 and 82 and the spudding cylinder 20. Pipes 85 and 86 are connected to the opposite ends of the pump 80, and pipes 88 and 90 are connected to the opposite ends of the pump 82. Pipes 85 and 88 are in turn connected with a pipe 92 while the pipes 86 and 90 are in turn connected with a pipe 94. Valves E and F (Figs. 1 and 5) are mounted respectively in the pipes 86 and 85 by which the circulation of the fluid from the pump 62 to the cylinder 20 may be controlled. A by-pass line 100 having a valve B is connected between the pipes 85 and 86 and a by-pass line 102 having a valve A is connected between the pipes 88 and 90. A by-pass line 104 having a valve C is connected between the lines 85 and 90. A by-pass line 106 having a valve D is connected between the lines 86 and 88. The lower ends of the pressure fluid lines 92 and 94 generally consist of a high pressure flexible hose and preferably flexible hose 108 and 110 are connected between the upper ends of the pipes 92 and 94 and the ends of the spudding cylinder 20 (See Fig. 1).

The pumping cylinders 80 and 82 are double acting cylinders and act to pump fluid either directly to the spudding cylinder or to by-pass a part or all of the fluid being pumped to the other end of the pump cylinder. The pressure operating capacity of the spudding cylinder 20 is at least equal to the pumping capacity of the pumps 80 and 82. As illustrated in Fig. 5 the longest stroke of the spudding cylinder piston will be obtained when the valves A, B, C and D are closed, and the valves E and F are open. For the shortest stroke of the spudding cylinder the valve B should be closed, valve A should be open, valves C and D should be closed, while the valves E and F should be open. To obtain any desired length of stroke of the spudding cylinder piston, between the longest and the shortest stroke, the valves may be operated to circulate liquid from cylinders 80 and 82 and by-pass the desired amount in order to give the desired length of stroke. It will be

noted that the spudding cylinder and the pumps on both sides of the pistons are always full of liquid. Therefore, during the pressure stroke of the pump pistons, fluid will be forced from the non-pressure side of the spudding cylinder piston back to the non-pressure sides of the pumping pistons. On the return strokes of the pump pistons, fluid on the pressure side of the spudding cylinder piston will be returned to fill the pressure sides of the pump cylinders. The valves A, B, C, D, E, and F control the amount of liquid supplied to the pressure side of the spudding cylinder and control the distribution of liquid to the non-pressure sides of the spudding cylinder 20 and pumps 80 and 82.

The operation of the pressure supplying fluid pumps is a continuous uniform reciprocation and provides a pendulum-like reciprocation of the spudding sheave 30. This uniform back and forth motion tends to minimize the vibration and pulsation of the drilling cable and thus tends to cut down the strain and wear on the derrick and hoisting machine. The flexible hose in the piping connection is expandable and act as shock absorbers if the pressure of the hydraulic fluid rises suddenly due to the drilling tool movement particularly upon the upward stroke.

It will be apparent that as the well gets deeper and deeper the length of cable being raised and lowered increases and requires an added pressure in placing the loop in the cable. Therefore, the pressure of the operating fluid will increase to supply the desired pressure for placing the loop in the cable. The length of the shock absorbing hose may be varied to provide for the amount of pressure that will be encountered.

A pressure relief valve 112 is connected between the lines 92 and 94 closely adjacent the cylinder 20 and will prevent destructive forces acting on the spudding piston as the result of possible cumulative leakage past the pump or spudding cylinder pistons.

To provide for leakage in the pumps and feed lines a supply chamber 114 is connected with the lines 88 and 90 through check valves 116. Preferably the liquid in the supply chamber 114 is held under pressure by an air pump 118 which is operated with the usual throttle valve 119 in accordance with the pressure in the chamber 114 to maintain a uniform desired pressure in the chamber. When the pressure in the feed lines 88 and 90 falls below the predetermined pressure in the chamber 114, fluid will be supplied through the loaded check valves 116 to bring the pressure in the lines to the desired amount.

In Fig. 6 is illustrated an alternative form of mechanism for forming the cable loop. This mechanism is shown as mounted upon a mast 120 just below the crown sheave 14. A sheave 122 is rotatably mounted on a fixed axle 124 secured to the mast in position for the sheave to loosely engage the drilling cable 10. A loop-forming sheave 126 is journaled on an arm 128 of a bell-crank lever 130 which is pivoted on the axle 124. The other arm 132 of the bell-crank lever 130 is pivotally connected with a piston rod 134 which in turn is connected to a piston mounted within a spudding cylinder 136.

The end of the spudding cylinder opposite the lever 130 is pivotally connected with one arm of a bell-crank lever 138 pivotally mounted on the mast 120. The other arm of the bell-crank lever 138 carries a clamping shoe 140 which is arranged to press the drilling cable against a clamping jaw 142 which is mounted in fixed position on the

mast 120. The opposite ends of the cylinder 136 are connected by means of flexible hose 108 and 110 which in turn are connected with the above described fluid circulating pipes 92 and 94 for supplying fluid and removing fluid from the cylinder 136. When the cylinder 136 and sheave 126 are in the position illustrated in full lines in Fig. 6 the sheave will loosely engage the drilling cable and allow it to move freely. At the time pressure fluid is introduced into the cylinder through line 108 the piston in the cylinder will tend to move the bell-crank lever 138 into clamping position on the cable and thereafter the further introduction of pressure fluid to the cylinder 136 will act to move the loop-forming sheave 126 into the position shown in dotted lines to form a loop in the cable. Preferably, a spring is mounted in the cylinder 136 to move the loop-forming sheave 126 into the position shown in full lines, Fig. 6, and to hold the sheave in loose engagement with the drilling cable when the loop-forming mechanism is not in operation.

It will be understood that the loop-forming mechanisms shown in Figs. 1, 2 and 6 may be mounted on and used with either a drilling derrick or mast.

According to the provisions of the patent statutes, I have explained the principle and mode of operation of my invention and have illustrated and described what I now consider to be the best embodiment of it, as well as a modification thereof. However, I desire to have it understood that within the scope of the appended claims, the invention may be practiced otherwise than as specifically illustrated and described.

I claim:

1. In a hydraulic drilling machine comprising a derrick, a crown sheave rotatably mounted at the top of the derrick, a winding drum mounted at the base of the derrick, a drilling cable leading up from the drum over the crown sheave and down to a well-spudding drill attached thereto, the improvement comprising, a loop-forming cylinder having a piston therein with a rod projecting therefrom, a rotatably mounted sheave connected with the rod in a position to engage the section of the drilling cable extending from the crown sheave to the spudding tool, a fixed sheave mounted in the derrick in position to engage the cable a short distance below the point of engagement of the loop-forming sheave with the cable, a hydraulic pump mounted at the base of the derrick, and connections between the pump and the loop-forming cylinder to circulate liquid to and from the cylinder to operate the piston with a pressure and return stroke to form and release a loop in the cable for reciprocating the drill on the cable.

2. The drilling machine defined in claim 1 in which the fluid connections between the pump and the cylinder are expandable to provide for absorbing the shock effect of abnormal pressure created in operating the drilling tool.

3. The drilling machine defined in claim 1 in which a cable clamp is mounted to engage the cable between the crown sheave and the loop-forming sheave and an operating connection is provided between the cylinder and the clamp arranged to clamp the cable at the beginning of the loop-forming movement of the cylinder to prevent the impulse of the loop-forming load being placed on the crown sheave and the section of cable extending between the crown sheave and the winding drum.

4. The drilling machine defined in claim 3 in

which the loop-forming cylinder and piston are suspended by moveable links from the derrick and arranged to oscillate when pressure fluid is introduced into the cylinder to start the cable loop-forming stroke, said oscillation acting to move the clamp into clamping position on the cable.

5. The drilling machine defined in claim 3 in which the loop-forming cylinder is movably suspended by links pivoted to the crown block of the derrick with a fixed clamping jaw secured to the crown block in position to engage the drilling cable closely adjacent the crown sheave, a movable clamping jaw mounted on a lever secured to and movable with a cylinder linked pivot, and the pressure fluid connections between the pump and the cylinder being arranged to introduce fluid for the loop-forming stroke of the piston into the end of the cylinder opposite the loop-forming sheave.

6. The drilling machine defined in claim 4 in which the cable clamp is composed of one jaw mounted in fixed position near the top of the derrick adjacent the drilling section of the cable and a second jaw connected to and movable with a link for supporting one end of the cylinder whereby introduction of pressure fluid into the cylinder will act to move the jaws into clamping position and arrest the oscillatory movement of the cylinder and thereafter the continued introduction of pressure fluid into the cylinder will drive the piston into loop-forming position.

7. The drilling machine defined in claim 5 in which springs are connected between the derrick crown block and the oscillatable loop-forming cylinder to hold the loop-forming and fixed sheaves in loose engagement with the drilling cable when pressure fluid is not being circulated to the loop-forming cylinder.

8. The drilling machine defined in claim 1 in which the pump and cylinder are double acting and the hydraulic connecting lines between the ends of the pump and the cylinder are arranged to return the hydraulic fluid to the non-pumping side of the piston during each pressure stroke of the pistons.

9. The drilling machine defined in claim 6 in which a pressure relief valve is connected between the fluid lines at opposite ends of the cylinder to prevent a destructive pressure from being placed on the cylinder piston and fluid lines.

10. The drilling machine defined in claim 1 in which the pump is composed of two pump cylinders of different fluid pumping capacities which are operated simultaneously, and valves are mounted in the lines connecting the pumps with the cylinder by which the length of the loop-

forming stroke of the piston in the cylinder may be varied.

11. The drilling machine defined in claim 8 in which the fluid receiving capacity of the cylinder is at least equal to the combined pumping capacities of the two pumps.

12. In a hydraulic drilling machine comprising a mast, a crown sheave rotatably mounted at the top of the mast, a winding drum mounted at the base of the mast, a drilling cable leading up from the drum over the crown sheave and down to a well-spudding drill attached thereto, the improvement comprising, a loop-forming cylinder having a piston therein with a rod projecting therefrom and connected with one arm of a bell-crank lever pivoted on the mast, a loop-forming sheave rotatably mounted in the other arm of the bell-crank lever, a sheave rotatable on a fixed axis mounted on the mast, said sheave being positioned to engage the cable closely adjacent the point of contact of the loop-forming sheave with the cable, a hydraulic pump mounted at the base of the mast and connections between the pump and the loop-forming cylinder to circulate liquid to and from the cylinder to operate the piston with pressure and return strokes to form and release a loop in the cable for reciprocating the drill on the cable.

13. The drilling machine defined in claim 12 in which the connection between the cylinder piston rod and bell-crank lever is adjustable to vary the lengths of the pressure and return strokes of the piston in the cylinder.

14. The drilling machine defined in claim 12 in which a fixed cable clamping jaw is mounted on the mast adjacent the crown sheave in position to engage the drilling cable and a bell-crank lever is pivotally mounted on the mast with one arm connected to the loop-forming cylinder and the other arm carrying a clamping jaw positioned to be moved into engagement with the drilling cable opposite the fixed clamping jaw during the pressure stroke of the piston in the cylinder.
